(57) **CLAIM**

The ornamental design for a display screen with graphical user interface, as shown and described.

DESCRIPTION

FIG. 1 is a front view of a display screen with graphical user interface showing my new design;

FIG. 2 is a front view of a display screen with graphical user interface showing an alternative embodiment of my new design; and,

FIG. 3 is a front view of a display screen with graphical user interface showing an alternative embodiment of my new design.

The dashed broken line showing of the text, remainder of the graphical user interface and display screen is for environmental purposes only and forms no part of the claimed design.

1 Claim, 3 Drawing Sheets

FIG. 1

FIG. 2

FIG. 3
